(57) **CLAIM**

The ornamental design for a climbing structure, as shown and described.

DESCRIPTION

FIG. 1 is a front, left, top perspective view of a climbing structure, showing my new design;

FIG. 2 is a rear, right, bottom perspective view thereof;

FIG. 3 is a front elevational view thereof;

FIG. 4 is a rear elevational view thereof;

FIG. 5 is a left side view of the enlarged scale thereof;

FIG. 6 is a right side view of the enlarged scale thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 2;

FIG. 11 is an enlarged view of detail 11 in FIG. 2; and,

FIG. 12 is an enlarged view of detail 12 in FIG. 2.

The dashed broken lines in the figures are for the purpose of illustrating portions of the climbing structure and form no part of the claimed design. The dash-dot-dash broken lines in FIGS. 1 and 9 depict the bounds of the enlarged view and form no part of the claimed design.

1 Claim, 11 Drawing Sheets
